UNITED STATES PATENT OFFICE.

JOSEPH CHIDLEY, OF CLEVELAND, OHIO.

SPRINKLER DEVICE FOR LOCOMOTIVES.

1,091,631.

Specification of Letters Patent. Patented Mar. 31, 1914.

Application filed September 23, 1912. Serial No. 721,929.

To all whom it may concern:

Be it known that I, JOSEPH CHIDLEY, a citizen of the United States, residing at Cleveland, in the county of Cuyahoga and State of Ohio, have invented certain new and useful Improvements in Sprinkler Devices for Locomotives, of which the following is a specification.

This invention has reference to the provision of an improved form of sprinkler device for locomotives, such as is used for example in sprinkling water over the coal or cleaning up around the engine or cab. The first of the objects of this present invention is the construction of a device of the character specified which will provide in a compact, efficient, and simple form, a means for using a limited or predetermined quantity of water in the tank in the manner indicated, and at the same time will not be liable to scald or injure the fireman, engineer, or bystanders, through the back flow of steam or hot water, as frequently happens in connection with the arrangement in common use in which a sprinkler hose is connected to the injector mechanism in such position that if the injector breaks or backs up, the steam or hot water will flow out through the sprinkler hose—an occurrence which is not at all uncommon.

In order that my invention may be better understood, I have illustrated the same in preferred form in the accompanying drawings, wherein—

Figure 1 is a partial plan view showing a locomotive tender construction with my improvements applied thereto; Fig. 2 is an elevation partly in section, showing a side view of the apparatus shown in Fig. 1; Fig. 3 is an end sectional view with part of the apparatus in elevation; Fig. 4 is a detail of one form of valve mechanism I employ, and Fig. 5 is another view of the valve device shown in Fig. 4.

Referring now more particularly to Figs. 1, 2, and 3, it will be seen that in the lower portion of the tender therein indicated I have located a tank 6 which in order to reduce corrosion to a minimum is preferably made of cast metal and is located at or adjacent to the bottom of the water containing portion of the tank or tender, and is made preferably of small vertical dimension, but considerable size laterally and longitudinally so as to be capable of containing a sufficient quantity of water for an or-

dinary sprinkling operation. This tank is in general a closed receptacle except for the provision therein of an outlet pipe 7 which starts near the bottom of the tank and extends upwardly to a point normally above the ordinary height of the water and is connected with a sprinkler hose 8. Another connection to the tank is through the valvular device 9 which is coupled up with the pipe 10 that supplies air pressure to the tank through a manually controlled three-way cock or valve device 11 that has a supply from some convenient source of air pressure, as for example the main reservoir of the air brake system not shown in the drawings but well known in the art. The valvular device 11 should be located somewhere within convenient reach of the fireman or person operating the sprinkler.

As is evident from examination of Figures 4 and 5, the valvular device 9 comprises primarily a casing 12 to which there is connected the air inlet pipe 10. Within the casing 12 is arranged a piston 14 having a valve 15 connected therewith in position to close the water inlet opening 16 when the parts are in the position shown in Figure 4, but to open when the piston is depressed to its lower-most position in the chamber of the casing 12, and allow water to flow freely down through the opening 16 and out laterally through the series of openings 17 to fill the water receptacle 6 from the water in the tender or tank.

Arranged at a suitable point within the cylinder of the casing 12 there is another opening 18 which is uncovered when the piston is in its uppermost position with the valve 15 closed, so as to allow the air which has closed the valve 15 to flow out through the passage 19 and expand in the upper portion of the water receptacle 6, exerting a downward pressure upon the water therein, such as will drive the water out through the pipe 7 and sprinkling hose 8.

The operation of my invention is as follows. With the parts arranged as shown, when it is desired to sprinkle the coal or use the sprinkling device, the three-way cock or manually controlled means 11 is turned so as to admit air from the main reservoir or other air supply source to the inlet pipe 10, thence to the casing 12 whereupon it acts against the piston 14 to force the piston upward and seat the valve 15, uncovering the port 18 and flowing around through the pas-

sage 19 to fill the upper part of the water reservoir or receptacle 6, and the water from the main tender or tank being thus cut off, the pressure confined within the closed 5 water receptacle 6 will force the water out through the pipe 7 and the sprinkler hose 8 in a stream that will continue to flow until substantially all the water, or nearly all the water, in the closed receptacle 10 6 has been discharged, the receptacle being made of at least sufficient size to supply the requirements of any ordinary sprinkling operation. When the sprinkling is to be stopped the valve 11 is closed and the lateral 15 vent or three-way opening 11* therein allows the air to escape from the receptacle 6 and the underside of the piston, which latter then descends, the water above the valve 15 flowing downward and laterally through the 20 passage 17 and promptly filling the receptacle 6 ready for another operation.

It will be evident from examination of the action of the above mechanism that the admission of water to the receptacle 6 is substantially co-incident with the closure of the air supply which has been used in sprinkling, and vice versa, that is to say, that as soon as the air supply is admitted through the valve 11 the valvular device 9 will automatically operate to cut off the water connection from the main tank to the closed receptacle or reservoir 6. While I prefer the arrangement of valve device shown, it is obvious that other specific embodiments of 35 valvular mechanism could be utilized to obtain the same operations and relations between the manual controlling means for the air supply and the means which controls the admission of water to the closed reservoir.

40 Having thus described my invention and illustrated its use, what I claim as new and desire to secure by Letters Patent, is the following.

1. A sprinkler device for locomotives comprising in combination a closed water reservoir; a valve casing mounted in the reservoir and connected to a source of water supply; the said casing having a liquid flow port establishing communication between the 45 source of water supply and the interior of the reservoir, an air inlet port, and an air outlet port opening into the interior of the reservoir; a valve in the casing, coincidentally controlling the liquid flow port and the air 50 outlet port and normally in open position

uncovering the liquid flow port and covering the air outlet port; means for supplying air pressure to the inlet port; and a liquid discharge outlet leading from the reservoir; the said valve being moved to closed position 60 covering the liquid flow port and uncovering the air outlet port on admission of air pressure into the casing.

2. A sprinkler device for locomotives comprising in combination a closed water reservoir; a valve casing mounted in the reservoir and connected to a source of water supply; the said casing having a liquid flow port establishing communication between the source of water supply and the interior of the reservoir, an air inlet port, and an air outlet port opening into the interior of the reservoir; a valve in the casing coincidentally controlling the liquid flow port and the air outlet port and normally in open position 70 uncovering the liquid flow port and covering the air outlet port; means for supplying air pressure to the inlet port; and a discharge pipe leading from the reservoir; the said valve being moved to closed position covering the liquid flow port and uncovering the air outlet port on admission of air pressure into the casing.

3. A sprinkler device for locomotives comprising in combination a closed water reservoir; a valve casing mounted in the reservoir and connected to a source of water supply; the said casing having a liquid flow port establishing communication between the source of water supply and the interior of the reservoir, an air inlet port, and an air outlet port opening into the interior of the reservoir; a valve in the casing coincidentally controlling the liquid flow port and the air outlet port and normally in open position 80 uncovering the liquid flow port and covering the air outlet port; means for supplying air pressure to the inlet port; and a liquid discharge pipe leading from the reservoir, said pipe being entirely unobstructed whereby 100 the water will freely and quickly discharge therefrom when air pressure is cut off; the said valve being moved to closed position covering the liquid flow port and uncovering the air outlet port on admission of air 105 pressure into the casing.

JOS. CHIDLEY.
